UNITED STATES PATENT OFFICE.

WILLIAM D. IIENRY, OF ALLEGHENY, PENNSYLVANIA.

DESIGN FOR A TILE.

SPECIFICATION forming part of Design No. 24,636, dated August 27, 1895.

Application filed March 9, 1895. Serial No. 541,194. Term of patent 14 years.

to all whom it may concern:

Be it known that I, WILLIAM D. IIENRY, a citizen of the United States, residing at Allegheny, in the county of Allegheny and State of Pennsylvania, have invented and produced a new and original Design for Tile or Lintel for Fireproof Floors, of which the following is a specification, reference being had to the accompanying drawing.

The figure is a perspective view of a tile or lintel, illustrating my design.

My design consists of an oblong tile, hollow, as shown, the ends *a a* of the same being beveled, substantially as shown, and having rectangular slots *b b* near the bottom thereof, the

top of said tile having formed therein a groove *c*, extending the entire length of the same, giving it the appearance of a trough through the center of the top.

Having described my invention, what I claim is—

The design for a tile, substantially as herein shown and described.

In testimony that I claim the foregoing I hereunto affix my signature this 28th day of January, A. D. 1895.

WILLIAM D. IIENRY. [L. S.]

In presence of—
JAS. J. MCAFEE,
C. A. WILLIAMS.
